UNITED STATES PATENT OFFICE.

JAMIE H. BATCHELOR, OF SAVANNAH, GEORGIA, ASSIGNOR TO CARL ESPY, OF SAVANNAH, GEORGIA.

VAPORIZER FOR GAS-ENGINES.

1,233,744.

Specification of Letters Patent. Patented July 17, 1917.

Application filed April 20, 1916. Serial No. 92,517.

To all whom it may concern:

Be it known that I, JAMIE H. BATCHELOR, a citizen of the United States, residing at Savannah in the county of Chatham and State of Georgia, have invented certain new and useful Improvements in Vaporizers for Gas-Engines, of which the following is a specification, reference being had to the accompanying drawings.

10 This invention relates to an improved vaporizer for gas engines and has for its primary object to provide simple and effective means for vaporizing the lower grades of hydro-carbon fuels, such as kerosene, 15 whereby the same may be utilized for the propulsion of engines of that type commonly employed for driving automobiles and other vehicles.

It is a more particular object of my invention to provide improved means for utilizing the exhaust from the engine for heating the gaseous mixture before its admission to the intake manifold.

It is one of the detail objects of the invention to provide an exhaust manifold having a receiving chamber for the mixture and a compartment inclosing the intake manifold, and a plurality of pipes having relatively large surface area extending through the exhaust manifold and connected to the intake manifold.

It is an additional general object of my invention to provide effective and reliable means for converting kerosene and gas into a properly vaporized, readily combustible mixture so that it may be employed in the ordinary type of gasolene engine with highly satisfactory results.

With the above and other objects in view, 40 my invention consists in the novel features of construction, combination and arrangement of parts to be hereinafter more fully described, claimed and illustrated in the accompanying drawing, in which,

45 Figure 1 is a vertical sectional view through a portion of a gasolene engine, showing my improved kerosene vaporizer applied thereto;

Fig. 2 is a section taken on the line 2—2 50 of Fig. 1;

Fig. 3 is a section taken on the line 3—3 of Fig. 2;

Fig. 4 is a detail section taken on the line 4—4 of Fig. 1.

55 Referring in detail to the drawing, 5 des-

ignates the engine cylinder which may be of any ordinary or approved construction and is provided with the usual intake port 6 having a valve 7.

The exhaust manifold, generally indicated by the numeral 8, may be mounted upon one side of the block of engine cylinders in any preferred manner. This exhaust manifold is suitably connected to the exhaust ports, as indicated at 9, and is provided with an upper longitudinally extending compartment 10 and the lower compartment 11. These compartments of the exhaust manifold are separated by a longitudinally extending wall 12. Adjacent to one end of the upper compartment 10 of the exhaust manifold, an inlet chamber 13 is provided, to which the supply pipe 14, extending from the carburetor, is connected. To the vertical wall 15 which separates this chamber from the compartment 10 of the manifold, the pipes or conduits 16 are connected at one of their ends and receive the mixture which is admitted to said chamber. These pipes are preferably of flat, elongated form in cross-section, as shown in Fig. 4, so as to afford an extensive surface area. The opposite end of the exterior wall of the exhaust manifold 8 is curved or rounded as shown, and the pipes 16 are extended in concentric relation thereto and downwardly into the lower compartment 11 of the manifold.

17 designates the intake manifold which is arranged within the lower chamber 11 of the exhaust manifold and is connected to the intake ports 6 of the engine cylinders. This intake manifold is formed with a depending portion 18, to which the other ends of the pipes or conduits 16 are connected.

Within the horizontally disposed portion 95 of the intake manifold 17, a pipe 19 is disposed, said pipe being closed at its opposite ends and having the pipe 20 connected to its central portion. This latter pipe extends outwardly through the walls of the intake 100 and exhaust manifold and is formed with a flattened, substantially semi-circular portion 21. The pipes 19 and 20 and the curved extension 21 of the latter, are filled with water. The pipe 20 is formed of metal which will 105 expand appreciably under an increase in temperature. The end of the curved portion 21 of the pipe 20 has a contact member 22 suitably secured thereon, to which the ground wire 23 is connected. A tubular rod 110

24 extends through the front wall of the exhaust manifold and into the depending portion 18 of the intake manifold. This rod is of copper or other metal of high electrical conductivity and is inclosed within a larger tube 25, one end of which has threaded engagement in a suitable boss on the wall of the manifold. A wire 26 connected in the magneto circuit or any other suitable source of supply, is electrically connected to the end of the tubular rod 24 and a second wire 27 connects said rod to a contact member 28 which is mounted upon a suitable bracket element 29 fixed to the tube 25.

15 Immediately below the extremity of the curved portion 21 of the pipe 20, an air inlet valve 30 is mounted upon the wall of the exhaust manifold, said valve being normally closed. The upper end of the valve stem 31. 20 is closely contiguous to the extremity of the expandible element 21.

In the operation of the device, the mixture of kerosene and air enters from the pipe 14 into the chamber 13 and, from said chamber, passes through the several pipes 16. The exhaust from the engine cylinders is admitted to the upper compartment 9 of the exhaust manifold, and by contact of the highly heated burned gases with these pipes, the mixture passing therethrough also becomes highly heated. The contact 22 on the end of the expandible pipe 21 is normally engaged with the contact 28 so that the electric circuit is closed and the tubular rod 24 thus becomes very highly heated and the end portion of this rod projecting into the intake manifold 17 further heats the mixture as it enters the intake manifold. This heated mixture will also heat the pipe 19 and the water contained therein. As the temperature of the water gradually rises, the curved extension 21 of the pipe 20 will expand, as it is not desirable to heat the interior of the manifold above a certain degree, say 150°, at which temperature the kerosene vapors would become separated or dissipated so that a good combustible mixture would not be obtained. Upon the expansion of this water-filled tube 21, the contact 22 is moved away from the contact 28 and the electric circuit is broken. This end of said tube will almost immediately engage with the valve stem 21 and opens the air intake valve 20 so that atmospheric air may 55 enter the inlet manifold, thereby reducing the temperature of the same. Thus, the gaseous mixture passing through the intake manifold is maintained at a constant even temperature. I have found in actual practice that, by the provision of the flat tubes or conduits 16, the kerosene is thoroughly vaporized, as an extensive surface is afforded with which the exhaust gases from the engine cylinders may contact. By the provision 60 in addition, of the electrically heated

rod extending into the intake manifold, the possibility of solid or unvaporized constituents of the kerosene entering the engine cylinders, is practically eliminated and a proper combustible mixture assured. It has heretofore been impossible to properly vaporize kerosene simply by extending the supply pipes or conduits into the exhaust manifold, but by the arrangement of the exhaust and intake manifolds as shown, and the flat form of conduit having a very extensive surface exposed to the exhaust gases, the mixture will first be heated to a high degree in its passage through the conduits so that, by the additional heating of the intake manifold through the medium of the electrically heated tubular rod extending within the same, the inadequacy of vaporizers of this type for the purpose of utilizing the lower grades of hydro-carbon fuels, is overcome. The exhaust gases, after passing through the lower compartment 11 of the manifold, are exhausted through the ordinary muffler to the atmosphere.

From the foregoing description, taken in connection with the accompanying drawing, it is believed that the construction, manner of operation, and several advantages of the invention will be clearly and fully understood. The device, while exceedingly simple in its construction, has been found by repeated tests to be highly satisfactory in practical use and to materially reduce the operating cost of motor vehicle engines by the use of a low grade hydro-carbon fuel such as kerosene which is relatively inexpensive. I have also demonstrated that, by means of the present invention, kerosene may be used as fuel without any reduction of power over that obtained by the use of gasoline, and in some instances the power obtained was even increased. In the accompanying drawing, I have illustrated one desirable mounting and arrangement of the several parts of the device, but it will, of course, be understood that the manifold construction, as well as the mounting and arrangement of the electrically heated tube and the expandible circuit closer and valve opening device may be changed as desired, in accordance with the particular type of engine upon which the device is to be employed. I, therefore, reserve the privilege of adopting all such legitimate modifications as may be fairly embodied within the spirit and scope of the invention as claimed.

Having thus fully described my invention, what I desire to claim and secure by Letters Patent is:

125 The combination with an internal combustion engine having intake and exhaust ports, of an exhaust manifold having upper and lower compartments, said upper compartment being connected to the exhaust ports, 130

said manifold being provided with an inlet chamber at one end of the upper compartment, an intake manifold centrally located within the lower compartment and connected to the intake ports of the engine, and a plurality of transversely elongated conduits in communication at one of their ends with said inlet chamber and extending through the upper compartment and into

the lower compartment, the other ends of 10' said conduits being connected to the intake manifold.

In testimony whereof I hereunto affix my signature in the presence of two witnesses.

JAMIE H. BATCHELOR.
